UNITED STATES PATENT OFFICE.

DAVIS S. BOYDEN, OF ALLSTON, MASSACHUSETTS.

OVERLOAD-INDICATING APPARATUS FOR TRANSFORMERS.

Application filed June 16, 1921. Serial No. 478,205.

To all whom it may concern:

Be it known that I, DAVIS S. BOYDEN, a citizen of the United States, residing at Allston, in the county of Suffolk and State 5 of Massachusetts, have invented certain new and useful Improvements in Overload-Indicating Apparatus for Transformers; and I do hereby declare the following to be a full, clear, and exact description of the invention, such as will enable others skilled 10 in the art to which it appertains to make and use the same.

The present invention relates to an improvement in overload indicating apparatus 15 for transformers.

The present invention constitutes an improvement upon the construction illustrated and described in the application executed by me of even date herewith for an im- 20 provement in transformers.

The object of the invention is to produce an overload indicating apparatus having provision for indicating the attainment of different degrees of overload, and to this 25 end the invention consists in the apparatus hereinafter described and particularly defined in the claims.

In the accompanying drawings illustrating the preferred form of the invention, Fig. 30 1 is an elevation of a transformer showing the overload indicating apparatus in position; Fig. 2 is a rear elevation of the apparatus with the box removed; Fig. 3 is a vertical section taken on the line 3—3, Fig. 35 2, showing the box; Fig. 4 is a horizontal section taken on the line 4—4, Fig. 3; and Fig. 5 is an enlarged detail hereinafter referred to.

The overload indicating apparatus illustrated in the drawings is described as follows: This apparatus consists of a heat 40 sensitive element 10 supported on the lower end of a tube 11 from the base 12, adapted to be inserted through the cover of the transformer 20, into the oil 21 and in close proximity to the coil 22. The instrument is secured in place in the cover by means 45 of a nipple 13 which is inserted in the hole in the cover of the transformer and secured in place by a nut 14. Upon the base 12 is 50 mounted a plate 15 which carries standards 16 supporting two horizontal plates 17, 18. These standards and plates constitute the frame work of the indicating portion of the 55 apparatus. The heat sensitive element consists of a coil or spiral 30 of any usual or

preferred construction, to which is attached the vertical rod 31 adapted to be turned by the heat sensitive coil 30 with variations in temperature of the oil in the transformer. 60 The upper end of the rod 31 passes through a hole in the plate 17, which supports and steadies the rod in position. Near the upper end of the rod 31 is secured a collar 32. Loosely mounted on the upper end of the 65 rod and resting on the collar 32 is the trip disk 33, which is held from endwise movement of the rod by a collar 34 secured by a screw 35 to the rod 31. The trip disk 33 is provided with a pin 36, and the collar 34 70 is provided with a pin 37. A hair spring 38 is bent upon itself and embraces the pin 36 at one end, and is secured to the pin 37 at the other end by means of a screw 39. The disk 33 is also provided with a second pin 75 40 against which the pin 37 is held by the tendency of the hair spring 38 to straighten out. This arrangement is such that the trip disk 33 is normally held in position with its pin 40 against the collar pin 37, so that as the temperature rises, the rod 31 turns 80 counterclockwise, as viewed in Fig. 5, and turns the trip disk by means of the engagement of the collar pin 37 with the disk pin 85 40. The semaphore 50 is mounted to slide vertically on the rods 51, which are supported at the bottom in the plate 15 and at the top in the plate 18. To the semaphore 90 is attached a spring detent 52, the lower end of which normally rests upon the upper surface of the trip disk 33, as shown in Figs. 2, 3 and 4. When the rod 31 is turned by a rise in the temperature, the trip disk moves counter-clockwise bringing the notch in the 95 disk under the lower end of the spring de- tent 52, thereby permitting the semaphore 50 to fall. This spring detent, however, is provided with a shoulder 53, which, when the trip disk passes out from under the 100 lower end of the spring detent 52, engages the trip disk in the descent of the sema- 105 phone. This arrests the descent of the sema- phone before it has completed its fall, and holds the semaphore in what may be called its middle or tolerable overload position, until the attainment of a second critical temperature, when the trip disk moves out from under the shoulder 53, thus permitting the semaphore to complete its descent.

Thus it will be seen that in this apparatus, upon the attainment of the first critical temperature, the semaphore drops to middle 110

or tolerable overload position, and indicates the attainment of the first critical temperature. If the temperature now falls, the turning of the rod 31 is not prevented because the hair spring 38 permits the rod to turn, resisted only by the slight resistance offered by the hair spring to such return turning movement. If observed at this time, the observer will understand that the temperature of the transformer rose to the first critical point, and while it may have risen above that point, it did not attain the second critical point. He may then reset the semaphore by means of the resetting device, consisting of the lever 60, carrying the pin 61, which is adapted to engage the under side of the semaphore 50, to lift it up when the push pin 62 is pressed upward to actuate the resetting lever 60, the latter being pivoted at 63 on a bracket in the upper end of a stud 64, within which the push pin 62 is mounted. If the temperature of the transformer now rises to the first critical point, the semaphore will again drop to its middle position and remain in that position until reset, or until the second critical temperature is reached, when the semaphore will be permitted to drop to the limit of its descent.

This semaphore and the devices above described are enclosed within a box 70, provided with a window 71, which box is secured to the plate 15 by screws entering through the screw-holes 72, and in the bottom of the plate 15. When the first critical temperature is reached, the semaphore is half exposed through the window 71. When the second critical temperature is reached, the semaphore is wholly exposed through the window 71.

This overload indicating apparatus in use on transformers will, therefore, indicate by the position of the semaphore whether or not the transformer has been subjected to an overload, and whether or not such overload was the moderate overload corresponding to the middle position of the semaphore, or the greater overload corresponding to the bottom position of the semaphore. Thus the character of the overload to which the indicating apparatus is subjected, is indicated. The middle position of the semaphore may conveniently be taken as indicating a tolerable overload, while the bottom position of the semaphore may be taken to indicate an intolerable overload, so that when a transformer is subjected to tolerable overload, its identity may be noted and it may be made the subject of a regular and frequent inspection, because it is a transformer which, while liable to intolerable overload, does not require immediate replacement, whereas when a transformer shows intolerable overload, it should be replaced at once.

The temperature of the air in which any given transformer is located will determine

the rate of dissipation of heat from the transformer. Thus, when the temperature of the air is at high summer heat, heat generated by the transformer will be dissipated more slowly than when the temperature is at low winter points. This fact renders any given transformer more liable to be burned out in winter than in summer, because the oil being deprived of its heat by radiation more rapidly in winter than in summer, will have a lower temperature than in summer, even when the transformer coils are hotter, with the result that with the same overload indicating apparatus set for the same critical temperatures, the liability of burning out will be greater in winter than in summer, as stated. The present overload indicating apparatus, since it has two indications of overload, or two indications of arrival at higher temperatures, affords provision for indicating dangerous temperature both in summer and in winter. In summer upon the indication of tolerable overload, or the attainment of a first critical temperature, the observer will reset or note the condition, and put the transformer under observation. Then when in summer intolerable overload, or the second critical temperature point, is reached, the observer will know and understand that the transformer must be replaced by another of larger capacity. In winter time, however, this semaphore, on the arrival of what in summer would be a condition of tolerable overload, may be taken to indicate a condition of intolerable overload, and replacement of the transformer should be made at once. So the apparatus has a double temperature indication in summer, and a single useful temperature or overload indicating provision in winter.

Having thus described the invention, what is claimed is:—

1. Overload indicating apparatus for transformers having, in combination, a heat sensitive element, a semaphore, a rod adapted to be rotated by the heat sensitive element provided with a trip disk connected to the rod to yield in one direction, and to be positively moved thereby in the other direction, said semaphore being provided with a part to engage the trip disk.

2. Overload indicating apparatus for transformers having, in combination, a heat sensitive element, a semaphore, a trip member connected with the heat sensitive element, a detent connected with the semaphore, the trip member and detent having provision for permitting movement of the semaphore from non-indicating position, first to tolerable overload indicating position, and second to intolerable overload indicating position.

3. Overload indicating apparatus for transformers having, in combination, a heat sensitive element, a semaphore, a rotary trip

disk connected with and actuated by the heat sensitive element, a detent connected with the semaphore having two portions adapted to engage the trip disk at positions 5 of the semaphore indicating normal load and tolerable overload.

4. Overload indicating apparatus for transformers having, in combination, a heat sensitive element, an indicator, and connections 10 between the heat sensitive element and the indicator to normally retain the indicator in inoperative position constructed and arranged to permit the indicator to move into position for indicating tolerable 15 overload at a certain predetermined temperature and to a second position for indicating a greater overload at a higher predetermined temperature and for preventing the indicator from moving to inoperative 20 position.

5. Overload indicating apparatus for transformers having, in combination, a heat sensitive element, a semaphore, means for normally retaining the semaphore in non- 25 indicating position, and connections between the heat sensitive element and the retaining means for allowing the semaphore to first move into and to be retained in tolerable overload indicating position at a 30 predetermined temperature and to thereafter move into and be retained in intolerable overload position at a higher predetermined temperature.

6. Overload indicating apparatus for 35 transformers having, in combination, a heat sensitive element, a semaphore, and connections between the heat sensitive element

and the semaphore to normally hold the semaphore in non-indicating position constructed and arranged to permit the semaphore to move by a step-by-step movement for indicating a plurality of different overload conditions to which the transformer may be subjected having provision for retaining it in such position.

7. Overload indicating apparatus for 40 transformers having, in combination, a heat sensitive element, an indicator normally retained in a first fixed non-indicating position, and connections between the heat sensitive 45 element and the indicator constructed and arranged to permit the indicator to first move to a second fixed position for indicating tolerable overload, and then upon further increase in temperature to a third 50 fixed position to indicate intolerable overload.

8. Overload indicating apparatus for 55 transformers having, in combination, a casing, a heat-responsive element, a trip mechanism connected with the heat-responsive element, a gravity actuated semaphore, and means cooperating with the trip mechanism 60 for holding the semaphore in non-warning position at normal temperature, means being provided whereby a predetermined increase in temperature will permit the semaphore to drop and stop at a predetermined 65 point, indicating tolerable overload, and to thereafter, upon increase in temperature, 70 permit the semaphore to drop another step to thereby indicate intolerable overload.

DAVIS S. BOYDEN.
